PRINTING CYLINDER PRESSURE SYSTEM

Lyman Perry Albaugh, Des Moines, Iowa, assignor
to Meredith Publishing Company, Des Moines,
Iowa, a corporation of Iowa

Application January 22, 1937, Serial No. 121,814

2 Claims. (Cl. 60—52)

An object of my invention is to provide a pressure system for the printing cylinders of a printing press in which provision is made, through a safety mechanism for relieving the pressure in 5 the event of the passage of an object through the press which would damage the printing cylinder if means were not provided for relieving the pressure.

With this and other objects in view, my invention consists in the construction, arrangement and combination of the various parts of 10 the device, whereby the objects contemplated are attained, as hereinafter more fully set forth, pointed out in my claims, and illustrated in the 15 accompanying drawing, in which:

Figure 1 is a side elevation of a portion of a printing press showing in section one of my hydraulic pressure mechanisms applied to one of the bearings of one of the printing cylinders and 20 showing diagrammatically a pump for maintaining the fluid in the system under substantially constant pressure.

Figure 1a is an enlarged sectional view of the 25 hydraulic pressure mechanism showing the parts in a different position as a result of operation of a safety break block in the mechanism.

Figure 2 is a sectional view on the line 2—2 of 30 Figure 1 showing the coaction of a bearing of the printing cylinder with guideways of the printing press frame; and

Figure 3 is an enlarged sectional view on the 35 line 3—3 of Figure 1 showing an end view of the break block in the hydraulic cylinder of my mechanism, and in section a projection interposed between the break block and the bearing of the printing cylinder.

On the accompanying drawing I have used the 40 reference numeral 10 to indicate the side frame of a printing press. Journaled in the side frame 10 on a shaft 12 is one of the printing cylinders 14, this being the one which is provided with packing. The other printing cylinder is indicated at 16, and this is the one provided with the 45 printing plates, although it is immaterial from the standpoint of the operation of my invention to which one of the printing cylinders my mechanism is applied.

The printing cylinder 16 has a shaft 18 which 50 is journaled in a pair of slidable bearings 20, one being provided for each end of the shaft, as well known, although the drawing, being a side elevation in Figure 1, illustrates but one of them. Each bearing 20 is slidable in a pair of 55 spaced guides 22 so that the cylinder 16 can be

moved toward or away from the cylinder 14 in the operation of the press.

Heretofore it has been customary to provide a screw threaded means for each bearing 20 for moving the cylinder 16 toward or away from the cylinder 14. These cylinders are provided with bearers 24 located at each end of the cylinder and having peripheries of substantially the same diameter as the packing and printing plates of the cylinders 14 and 16. The peripheries of 10 these bearers 24 are coincident with the pitch diameters of the gears (not shown) usually provided at the ends of the cylinders 14 and 16 for rotating them in synchronism.

During the operation of the printing press, 15 after the plates and packing have been adjusted to the diameter of the bearer, it is necessary, in order to secure the proper printing impressions on the paper fed through the press, that the bearings 20 be adjusted so that the peripheries 20 of the bearers are in contact and under a substantial pressure in addition to mere contact. Otherwise proper printing impressions cannot be secured.

Obviously with a screw threaded mechanism as 25 heretofore used for this purpose, the operator of the press cannot accurately adjust the bearings 20, as first the bearers must be brought into contact and then the proper amount of additional pressure applied.

It has been customary to bring the bearers into 30 contact by sighting between them and adjusting the bearings 20 until no light can be seen between the bearers and then turn the adjusting screws a predetermined portion of a revolution thereafter, or apply a certain pressure to the adjusting hand wheel for the screw, or use some other haphazard method. It is almost impossible to secure bearers which are of absolute uniformity in radius throughout their circumference. Accordingly as the cylinders 16 and 14 35 rotate, some portions of the bearers might contact and others would not. If the pressure is adjusted a certain degree beyond contact at one point, there is a strong possibility that at other 40 points the pressure would be greater or less, and if it is much greater, then a hot bearing results after a few minutes running of the press. With new bearers, new bearings and new cylinders 45 this possibility is minimized, but as soon as these parts become worn, especially if they wear more at one point than at another, then extreme difficulty is experienced in adjusting the parts to the proper position for uniform printing.

Also when adjusting the printing cylinders, 50

- the press can be operated at slow speed to test out whether or not it is printing properly, but when it is shifted to high speed for the printing process, it has been found that the pressure decreases at the higher speeds and, therefore, what was a good result at low speed is not satisfactory at the working speed of the press. It is then necessary to shut down the press again and adjust the cylinders tighter, always keeping in mind that they should not be adjusted too tightly because there is then unnecessary wear on the parts and also hot bearings which, of course, aggravate the condition. Even during a single run, the wear of the parts may throw off the adjustment so that the adjusting operation has to be gone through again before another run can be put through the press. These operations take considerable time and require extreme skill to secure best results.
- 20 I have, therefore, provided a pressure system which automatically maintains a constant pressure on the printing cylinder regardless of the condition of the bearings or bearers, and one which will compensate for any unevenness in the working parts of the press, as well as one which can be adjusted for different pressures while the press is in operation. My system has further advantages and flexibility of control, as will appear as the description thereof proceeds.
- 25 30 I remove the screw type of actuating mechanism for the bearings 20 and in place thereof substitute a hydraulic cylinder 26. This cylinder may be secured in position by cap screws 28, and has in it a piston 30. The piston 30 is backed by a cup leather 32 or other suitable packing may be provided. In front of the piston 30 I provide a break block B comprising an annular ring 34 and a diaphragm 36. Interposed between the diaphragm 36 and the bearing 20 is a projection 38 of less diameter than the ring and contacting with the diaphragm within the ring. The projection 38 may be formed on the bearing 20 as illustrated, or may be a separate part interposed between the bearing and the diaphragm, or be formed on the diaphragm.
- 35 40 One of the hydraulic cylinders 26 is provided for each bearing 20 of the press, some of which are provided with a plurality of pairs of printing cylinders although only one pair is shown on the drawing.
- 45 50 Each of the cylinders 26 is connected by piping 42 with three-way valves 44. (The connection to the cylinder on the far side in the drawing is indicated at 42'.) The three-way valve is connected with a pressure line 46 and with a return line 48, which lines may extend as at 46a and 48a on to the other pairs of cylinders (not shown).
- 55 60 A pump P is provided, the outlet of which is connected with the pressure line 46, and the intake 52 of which is connected with the return line 48, with an oil reservoir 54 interposed between the two. A pressure valve V-PR is illustrated and connected between the pressure and return lines 46 and 48. Accordingly, with the valve 44 in the full line position shown at 44a, oil will be pumped from the reservoir 54 to each of the cylinders 26 to maintain a substantially constant pressure therein, any excess of the predetermined pressure being relieved through the pressure valve V-PR so that a substantially constant pressure is maintained in the line 46 and consequently on the pistons 30.
- 65 70 Any time it is desirable to shut down the press, a valve V is opened, whereupon the oil being

pumped into the line 46 returns through the return line 48 instead of maintaining pressure on the pistons 30. The pistons will thereupon return to the bottoms of the cylinders 26 by return springs 56. At all times the pressure in the pressure line 46 is indicated by a gauge 58, and the pressure may be adjusted by adjusting the valve V-PR in the ordinary manner, since this is the usual type of pressure relief or by-pass valve.

75 10 I have found that preferably the piping 46 should extend above any of the cylinders 26 so as to obviate the possibility of air pockets developing in the system.

Any time it is desirable to relieve the pressure from one printing cylinder, but retain it on the others, the three-way valve 44 for that particular cylinder can be adjusted to the dotted position 44b, thus connecting the piping 42 and 42' with the return line 48 to relieve the fluid pressure from the hydraulic cylinders of that particular printing cylinder. Whenever the valve 44 is swung again to the full line position, however, the pressure will be put back on the printing cylinder and will be the same pressure as before without the necessity of any further adjustments other than manually swinging the valve 44 from one position to another.

80 30 From the foregoing description it is obvious that, regardless of the condition of the bearings 20 or bearers 24, the same pressure is maintained on the bearers throughout all degrees of rotation of the printing cylinders. Any low places in the bearers are taken care of instantly by movement of the bearings 20, with the same pressure being maintained behind them whether the low places are minute or of substantial depth. Thus unevenness of the parts is compensated for in a manner impossible with a screw adjusted bearing, and without any excessive pressure which 40 would cause heating of the bearings. Also each end of the printing cylinder is under exactly the same pressure at all times.

85 45 Obviously the spending of time, as heretofore required, for adjustment purposes is entirely eliminated, as whenever the operator wishes to place the cylinders under pressure, it is merely necessary to have the pump P operating and close the valve V. The pressure will remain the same on all cylinders of the press regardless of the 50 number of runs or the wear on parts of the press. Whenever it is desirable to change the pressure, the valve V-PR can be adjusted for this purpose, which is an extremely simple operation as compared to the former adjustments necessary. This 55 saving of time is a substantial item in the printing business.

90 60 My system also prevents cylinder damage, as ordinarily excessive pressure caused by thin foreign objects passing through the press can be 60 taken care of by the movement backwardly of the bearings 20, whereas heretofore these bearings were fixed by their screw adjustments so that such movement was not possible. After such an object passes through the press, the cylinders 30 again position the bearings 20 in the proper position for their predetermined working pressure. If any large object goes through which would require excessive movement of the bearing 20 so quickly that the piston 30 could not force the oil back through the piping 42 and 42' quickly enough to prevent the object from damaging the printing cylinder, then the diaphragm 36 breaks through (illustrated in 70 75 90 95 98)

Figure 1a after breaking), thus acting as a safety device to prevent cylinder damage.

If damage of the diaphragm occurs, the piston 30 would be moved forwardly by the oil pressure, but is limited by engagement of the break block B with the guides 22, while the projection 38 is of sufficient length to let the bearing 20 contact with the ring 34 of the break block only after the cylinder 16 has been moved a substantial space from the cylinder 14. Thereafter, of course, a new break block must be inserted, the breakage of this block being in response to an abnormal condition and, therefore, an exception rather than a rule during the operation of the press. Ordinarily the piston 30 will move back enough to permit objects to pass through the press without breakage, but the break block takes care of extreme conditions.

The bearers 24 are always in contact with the additional necessary pressure for printing, as predetermined by the setting of the valve V—PR, and as accurately indicated by the gauge 58, which indication is a feature of my invention having no possible equivalent whatsoever in the screw actuated types of movable bearings 20.

Thus I have provided for the first time means on a conventional press for measuring the pressure applied to the printing cylinders. Heretofore laboratory tests have been made to indicate the desired pressure, but never has there been any way in which this pressure could be measured or indicated, at all times during the operation of the press.

With my system it is possible to use the required pressure without any possibility of there ever being, during the operation of the press, an excessive pressure which would cause the bearings to overheat.

In Figure 1a the piston 30 and the break block B, it will be noted, are of slightly less diameter than the interior diameter of the cylinder 26. This is so that the piston floats in the cylinder so that the bearing 20, contacting with the break block, can wobble whenever there is excessive wear in it, or the shaft 18 is sprung slightly, and yet maintain the constant pressure throughout the rotation of the printing cylinder 16 instead of excessive pressure during certain portions of the revolution, and too light a pressure during other portions thereof, as experienced with screw adjusted types of bearings.

Using hydraulic pressure also compensates for any sprung or worn condition of the shaft 18 of the cylinder 14, as regardless of any eccentric operation of either the cylinder 14 or 16, the same pressure is maintained throughout their 5 operation.

With my system it is necessary to use only the power required to operate the cylinder with the desired pressure, whereas with the old system, because of the lack of means for determining the proper pressure, there is a possibility of putting on too much pressure and thus require the use of additional power to run the press. Obviously my system therefore reduces strain on the press and reduces the consumption of power. 15

Some changes may be made in the construction and arrangement of the parts of my device without departing from the real spirit and purpose of my invention, and it is my intention to cover by my claims, any modified forms of structure 20 or use of mechanical equivalents, which may be reasonably included within their scope.

I claim as my invention:

1. In a pressure system for a printing cylinder, a hydraulic cylinder for a bearing of the printing cylinder, a piston in said hydraulic cylinder and engaging the printing cylinder bearing to move the printing cylinder toward printing position, a hydraulic pipe system connected with said hydraulic cylinder, a break block interposed 30 between said piston and said bearing and means for retaining fluid in said pipe system and hydraulic cylinder under substantially constant pressure.

2. In a pressure system for a printing cylinder, a hydraulic cylinder for a bearing of the printing cylinder, a piston in said hydraulic cylinder and engaging the printing cylinder bearing to move the printing cylinder toward printing position, a hydraulic pipe system connected 40 with said hydraulic cylinder, a break block interposed between said piston and said bearing and comprising an annular ring, a diaphragm spanning said ring and a projection of less diameter than the ring and interposed between 45 the diaphragm and the bearing within the ring and means for retaining fluid in said pipe system and hydraulic cylinder under substantially constant pressure.

LYMAN PERRY ALBAUGH.
